UNITED STATES PATENT OFFICE.

ROBERT PENTLAND, OF JACKSONVILLE, FLORIDA.

PERPETUAL CALENDAR.

1,377,429.

Specification of Letters Patent.

Patented May 10, 1921.

Application filed November 15, 1920. Serial No. 424,208.

To all whom it may concern:

Be it known that I, ROBERT PENTLAND, a citizen of the United States, residing at Jacksonville, in the county of Duval and 5 State of Florida, have invented certain new and useful Improvements in Perpetual Calendars, of which the following is a specification.

This invention relates to perpetual 10 calendars and is designed more particularly as an improvement on the calendar shown in my Patent No. 1,348,044, issued July 27, 1920.

The patented calendar embodies two members one of which is rotatable with relation to the other and bears an annular series of centurial year ordinals adapted, in the rotation of the member, to be selectively positioned in relation to annual year ordinals 15 upon the other member, the last-mentioned member bearing groups of month designations, and the first-mentioned member bearing a plurality of monthly calendars adjusted in juxtaposition with relation to the 20 month designations upon rotation of this member. The said patented calendar is capable of manipulation so as to instantly produce a complete calendar for any year, past, 25 present or future, and which yearly calendar 30 will in all cases be an accurate one for the year selected, but in the use of the calendar it has been found that some confusion is 35 likely to be caused due to the fact that the monthly calendars must each embrace a total of thirty-one days, and it is necessary that the month designations be arranged in groups in such a manner that they do not, strictly speaking, read in chronological order. Therefore it is one of the principal 40 objects of the present invention to provide a calendar similar to the one disclosed in the said patent but so constructed that when the rotatable member of the calendar is adjusted to obtain a combination of centurial and 45 annual year ordinals representing a selected year, a complete calendar for that particular year, accurate in every respect, will be presented to view, the monthly divisions of the calendar being arranged in 50 definite chronological order and each embracing the exact total number of days in the month represented, so that having once produced the composite year date, the user of the device has immediately at command 55 a complete calendar for the selected year.

In the accompanying drawings: Figure 1 is a view in elevation looking at one side of the calendar embodying the invention;

Fig. 2 is a similar view looking at the 60 other side thereof, portions being broken away;

Fig. 3 is a vertical diametric sectional view through the calendar.

So far as its mechanical construction is 65 concerned, the calendar embodying the present invention comprises two face plates or sheets which may be of metal, celluloid, cardboard, or any other material suitable for the purpose, and one of which plates 70 is indicated by the numeral 1 and the other by the numeral 2, and a rotatable disk which is indicated by the numeral 3 and which may likewise be of any of the above 75 mentioned materials or any other material suitable for the purpose and which is mounted between the plates 1 and 2. The disk 3 may be of single or of double ply construction and the same is of general circular form as shown in Fig. 2 of the drawings, whereas the plates 1 and 2 are preferably 80 rectangular and have their margins secured together in any suitable manner. In order to rotatably mount the disk 3 between the plates 1 and 2, a pivot 4 may be 85 employed, the pivot in the present instance having its shank rotatably fitted through an opening 5 formed in the disk 2 and being provided with a substantially flat head 6 which contacts the outer face of this plate. 90 The shank of the pivot may be threaded into a turn button 7 secured to that face of the disk 3 which is presented at the face of the plate 1 and which may be grasped for the purpose of rotating the said disk 3. The 95 plate 1 is provided with a circular opening 9 concentric to the pivot 4, and upon the face of this plate surrounding and concentric to the opening there is printed an annular series of ordinals indicated by the 100 numeral 10, the series being divided into a plurality of sectors 11 by lines 12 which are radial to the pivot 4. There are seven of the sectors 11, and as a matter of convenience these sectors are indicated by the reference characters 11^a, 11^b, 11^c, 11^d, 11^e, 11^f, and 11^g. Beginning with zero in the sector 11^a, the several sectors are consecutively numbered in a clockwise direction as indicated by the numeral 13, and by reference 110

to Fig. 1, it will be observed that, taking any year ordinal, the ordinal designating the succeeding year will be found in the next adjacent sector, proceeding in the direction stated, with the exception that upon the occurrence of a leap year, one sector will be skipped. Thus for example, the year ordinal "18" comprising the eighteenth year of the first or any other century is found 10 in the sector 11^b, and the year ordinal "19" is found in the sector 11^c. However, as the twentieth year of any century is a leap year, the year ordinal "20" will not be found in the next sector 11^a but in the sector 11^e. 15 Likewise the ordinal "21" will be found in the sector 11^f, the year ordinal "22" in the sector 11^g, and the year ordinal "23" in the sector 11^a, but the year ordinal "24" representing a leap year will not be found in 20 the sector 11^b but in the sector 11^c. In practice, the year ordinals representing leap years will be printed in some distinguishing color or type so that they will not be confused with the year ordinals representing 25 ordinary years, and this method of distinction is clearly shown in said Fig. 1. It will now be apparent that beginning with the ordinal "00" in the sector 11^a, the year ordinals are consecutively arranged in numerical order in clockwise direction, succeeding year ordinals being located in next adjacent sectors in the direction stated except in the instance of the year ordinals representing leap years which are separated 30 from the preceding year ordinal by a skipped sector. Also it will be evident that while the year ordinals are arranged in sectors defined by the radial lines 12, they may as a matter of fact be considered as arranged in groups.

That face of the disk 3 which is exposed within the opening 9 in the plate 1 is divided by radial lines 14 into sectors 15 corresponding in number to the sectors 11, and 45 printed in an annular series upon the face of the disk and divided into groups by the lines dividing the sectors, are ordinals 16 representing centuriel years. As a matter of convenience the sectors 15 are severally indicated by the numerals 15^a, 15^b, 15^c, 15^d, 15^e, 15^f and 15^g, these sectors being arranged, in the order stated, in an anti-clockwise direction and being preferably designated by the ordinals ranging from 50 1 to 7 in the direction stated. The centuriel year ordinals beginning with "0" in the sector 15^f are arranged in numerical order throughout successive sectors in a clockwise direction, and while in the illustrated embodiment of the invention the highest centuriel ordinal is "20," it will be understood that the calendar may be given an unlimited range by extending the series of these ordinals to any desired degree. In the illustrated arrangement beginning with the cen-

turiel year ordinal "0" in the sector 15^f, we find the centuriel year ordinal "1" in the sector 15^e, the centuriel year ordinal "2" in the sector 15^d, and so on in numerical order throughout the series of sectors 70 in a clockwise direction until we reach the centuriel year ordinal "17" in the sector 15^c. As the calendar was changed in 1752, the centuriel year ordinal "17" in the said sector 15^c is supplemented by the annual 75 year ordinal "51" as indicated by the numeral 17 so as to recall to the user of the calendar the fact that the arrangement of centuriel year ordinals in successive sectors holds good up to and through the year 80 1751, but if it is desired to find any date or obtain the year calendar for the year 1753 or any subsequent year in the 18th century, it will be necessary to have reference to the sector 15^f in which appears another centuriel year ordinal "17" with a supplemental annual ordinal "53" preferably in a color distinguishing it from the centuriel year ordinal "17" in the sector 15^c.

At this point it may be stated that in the use of the calendar any complete year ordinal may be produced by rotating the disk 3 to such position as to register the particular sector 15 containing the centuriel year ordinal with the sector 11 containing the required annual year ordinal. Thus for example if it is desired to produce the complete calendar of the present year 1920, the disk 3 will be rotated to such position that the sector 15^b will be opposite the sector 11^a.

The centuriel year ordinals comprising the series 16 are to be employed in calculating all dates by the calendar as revised by Great Britain September 2, 1752, but in order that the present calendar may be employed likewise in calculating dates by the calendar as corrected by Gregory XIII on October 4, 1582, a second annular series of centuriel year ordinals, indicated by the numeral 18 is printed upon the face of the disk 3 within the bounds of and concentric to the series 16 and is divided into groups or sectors by the radial division lines 14. The arrangement of the ordinals in the series 18 is similar to that of the ordinals of the series 16, the former ranging from "0" to "15" with the supplemental ordinal "81," and then from "15" with the supplemental ordinal "83" to the ordinal "20."

The plate 2 is provided within an opening 19 preferably of rectangular form and located opposite the sector 11^a or "0" upon the plate 1, and printed or otherwise represented upon the face of the disk 3 opposite the face which bears the sectors 15, is an annular series of seven yearly calendars indicated by the numeral 20, adapted to be individually brought into position exposed within the opening 19, upon rotation of the said disk 3. These calendars are indicated 130

individually by the numerals 20^a, 20^b, 20^c, 20^d, 20^e, 20^f and 20^g and are located respectively opposite the sectors 15^b, 15^c, 15^a, 15^e, 15^f, 15^g, and 15^a, and by a comparison of the 5 several calendars 20^a, etc., it will be evident that the first day of the yearly calendar 20^a falls on Monday, the first day of the yearly calendar 20^b on Tuesday, the first day of the yearly calendar 20^c on Wednesday, etc.

- 10 In the use of the calendar should it be desired to obtain for example the year calendar for the year 2018, the disk 3 is urged to position such that the sector 15^a embracing the centurial year ordinal "20" will be opposite 15 and in registration with the sector 11^b in which appears the annual year ordinal "18." The sector 15^a is designated by the ordinal "1," as is also the sector 11^b and the sum of these ordinals is "2" which is the number of 20 the sector 15^b which is opposite the "0" sector 11^a thus indicating the fact that January 1, 2018, will fall on Monday, and by referring to Fig. 2 of the drawings it will be observed from the year calendar 20^a that 25 this is the fact. Assuming that it had been desired to produce the year calendar for the year 1866, the disk 3 would have been rotated to the same position as above described and as illustrated in Fig. 1, and as the centurial year ordinal "18" appears in the sector number "4" upon the said disk, the annual year ordinal "66" appears within the sector "5" upon the plate 1, and which sectors are in registration in this position of 30 the disk 3, the sum of the designating ordinals of the two sectors is 9, and subtracting from this sum which is greater than 7, the term of 7, we obtain as a result "2" which is the designating ordinal of the sector 15^b 35 which is in registration with the "0" sector 11^a, again indicating that January 1st, 1866, fell on Monday. Thus, taking the year calendar 20^a as a specific example, this calendar represents the true yearly calendar 40 for any year which may be composed by a combination of the centurial and annual year ordinals in the position of rotation of the disk 3 where the sector number "2" of the disk is in registration with the "0" sector 11^a. If the disk 3 is rotated to any other position as for example to compose the year 45 ordinal 1898, in which position the sector number "4" of the disk will be opposite the sector number "3" of the plate 1, the sector 50 number "7" of the disk would be in registration with the "0" sector of the plate 1, this number 7 corresponding to the sum of the numbers 4 and 3 of the sectors referred to and indicating that the first day of the calendar year 1898 fell upon Saturday or in 55 other words the seventh day of the week.

In case the composed year ordinal represents a leap year, the yearly calendars 20^a, etc. may still be successfully employed as 60 each embodies, in addition to twelve monthly

divisions representing an ordinary year, two additional month divisions for the months January and February, indicated by the numeral 21 and which may be employed in the event stated.

It is preferable that complete calendars 70 22 and 23 for the years 1582 and 1752 respectively be printed upon some portion of the article as a whole, such for example as upon the face of the plate 2 at relatively opposite sides of the opening 19 in the said plate.

While the designating ordinals for the two series of sectors will serve to indicate, in the manner above exemplified, the day of 80 the week on which the first day of any selective year will fall, these designating ordinals are provided primarily as a means for preventing error in the use of the device. For example if it is desired to obtain 85 a calendar for the present year (1920) it will be observed that the designating ordinal of the sector 15 in which the centurial year 90 19 appears is "2" and that the sector 11 in which the annual year 20 appears is designated by the ordinal "4." Thus before rotating the member 3 it may be readily determined by the user of the device that when he has rotated the member 3 to the proper position, the sector 15^f having the designating ordinal "6" (the sum of "2" and "4") 95 must be located opposite the zero sector 11^a.

It will be understood that the leap year month calendars 21 may have their dates printed in red or some other distinguishing 100 color.

Having thus described the invention, what is claimed as new is:

1. In a perpetual calendar, members one 105 rotatable with relation to the other, the second-mentioned member bearing a plurality of groups of annual year ordinals and the first-mentioned member bearing a plurality of groups of centurial year ordinals adapted to be selectively positioned with relation to 110 the groups of the second-mentioned member upon rotation of the first-mentioned member, and a plurality of yearly calendars upon the first-mentioned member arranged to be individually brought to a position indicated 115 upon the second mentioned member and each comprising an arrangement of year dates correct for any composition of centurial and annual year ordinals possible in such position of adjustment of the first-mentioned member from related groups of such ordinals upon the said members.

2. In a perpetual calendar, members one 120 rotatable with relation to the other, the second-mentioned member bearing a plurality of groups of annual year ordinals and the first-mentioned member bearing a plurality of groups of centurial year ordinals adapted to be selectively positioned with relation to 125 the groups of the second-mentioned member 130

upon rotation of the first-mentioned member, and a plurality of yearly calendars upon the first-mentioned member arranged to be individually brought to a position to be indicated upon the second-mentioned member in the rotation of the first-mentioned member, each of said yearly calendars comprising an arrangement of year dates such that when any one of the yearly 10 calendars is in the said indicated position, it will be correct for any possible combination of centurial and annual year ordinals from relatively positioned groups upon the two members forming a composite year ordinal.

15 3. In a perpetual calendar, members one rotatable with relation to the other, the second-mentioned member bearing a plurality of groups of annual year ordinals consecutively numerically indicated in a clockwise direction, the first-mentioned member bearing a plurality of groups of centurial year ordinals consecutively numerically designated in an anti-clockwise direction and adapted to be selectively brought to position 20 relative to the groups of annual year ordinals in the rotation of the said first-mentioned member, and a plurality of yearly calendars upon the first-mentioned member arranged, in the rotation of the said member, to be individually brought to a position indicated upon the second-mentioned member, each of the yearly calendars being located relatively opposite the respective group of 25 centurial year ordinals upon the first-mentioned member and each constituting a complete calendar for a year beginning on a predetermined week day, the total number of yearly calendars equaling the total number of days in a week and the arrangement of said yearly calendars with relation to the grouped centurial year ordinals upon the first-mentioned member being such that any year calendar in the indicated position will 30 constitute a correct calendar for any year ordinal composable by a combination of any of the centurial and annual year ordinals of any two groups related in the said position

35

40

45

of adjustment of the first-mentioned member.

4. In a perpetual calendar, members one 50 rotatable with relation to the other, the second-mentioned member bearing a plurality of groups of annual year ordinals consecutively numerically indicated in a clockwise direction, the first-mentioned member bearing a plurality of groups of centurial year ordinals consecutively numerically designated in an anti-clockwise direction and adapted to be selectively brought to position 55 relative to the groups of annual year ordinals in the rotation of the said first-mentioned member, and a plurality of yearly calendars upon the first-mentioned member arranged, in the rotation of the said member, to be individually brought to a position indicated upon the second-mentioned member, each of the yearly calendars being located relatively opposite the respective group of 60 centurial year ordinals upon the first-mentioned member and each constituting a complete calendar for a year beginning on a predetermined week day, the total number of yearly calendars equaling the total number of days in a week and the arrangement of said yearly calendars with relation to 65 the grouped centurial year ordinals upon the first-mentioned member being such that any year calendar in the indicated position will constitute a correct calendar for any year ordinal composable by a combination of any 70 of the centurial and annual year ordinals of any two groups related in the said position of adjustment of the first-mentioned member, the annual year ordinals which represent leap years being distinguished from 75 the other annual year ordinals, and each of said yearly calendars embracing, in addition to the twelve monthly calendars of the ordinary year represented, other monthly calendars for employment in an indicated leap 80 year.

In testimony whereof I affix my signature.

ROBERT PENTLAND. [L.S.]
